DESIGN FOR A LAMP SHADE

Isaac Batkin, New York, N. Y.

Application July 20, 1934, Serial No. 52,641

Term of patent 3½ years

To all whom it may concern:

Be it known that I, Isaac Batkin, a citizen of the United States, and a resident of the Borough of Bronx, city and State of New York, with a post office address at No. 19 West 21st Street, in the Borough of Manhattan, city and State of New York, have invented a new, original, and ornamental Design for Lamp Shades, of which the following is a specification, reference being had to the accompanying drawing, forming part thereof.

I claim:

The ornamental design for a lamp shade, as shown and described.

ISAAC BATKIN.
